Inventor
E. F. Jager

By J. F. Wilson Atty

UNITED STATES PATENT OFFICE.

EARL F. JAGER, OF CHICAGO, ILLINOIS.

RAILWAY-CAR-DOOR CONSTRUCTION.

Application filed November 12, 1924. Serial No. 749,361.

This invention relates to the art of doors for freight and express cars, and has reference more particularly to doors of the sliding type which are suspended from a track-way above the door opening and slide lengthwise of the side of the car in opening and closing the door opening.

Railway car doors of this type are commonly equipped on their lower edges with a depending flange that co-operates with upwardly and outwardly projecting guide brackets attached to the sill of the car body, to hold the door from swinging outwardly or away from the side wall of the car under the pressure of the lading or lateral swaying of the car body. These guide brackets project outwardly of the vertical plane of the door opening and are not infrequently broken, bent or otherwise damaged by contact with the lading or trucks backing up to the door opening.

One object of my present invention is to provide improved means for holding the car door against outward swing from the vertical plane of the opening that shall be entirely free from the objections above noted inhering in the use of the common outwardly projecting guide brackets. To the attainment of this object, the structure of my present invention is equipped with one or more stationary door guiding and retaining members located inside the vertical plane of the outer edge of the door sill, and the bottom edge of the door is equipped with a co-operating movable guide member that overlaps and lies behind the stationary guiding member, so that the entire door guiding and retaining device is located wholly back of the vertical plane of the outer edge of the door sill, thus eliminating danger of damage thereto from lading or trucks.

Another object is to provide an improved door guiding and retaining structure where-in in the outward thrust or pull on the guiding member that is attached to the car floor and sill will be practically in line with the fastening bolts and rivets of said guiding member, thus lessening the breaking strain on such bolts and rivets as compared with the known construction above referred to.

Another object is to supply a simple and

efficient provision for drawing the door snugly against the opening when the door is closed. 55

Another object is to provide an improved construction whereby the door shall be held against outward pressure at its bottom over its entire width. 60

Still another object is to provide a construction which shall be theft-proof against the possibility of entering the car by raising the door over the guiding and retaining brackets and then swinging it clear of the latter, as it is often done with the ordinary car door. 65

Other objects and many of the attendant advantages of the invention will be apparent from the following detailed description, taken in connection with the accompanying drawings wherein I have illustrated one practical embodiment of the principle of the invention, and in which— 70

Fig. 1 is a fragmentary elevation of the lower portion of the side wall of a freight car containing my improved door and door guiding means; 75

Fig. 2 is a horizontal section of the same taken on the line 2—2 of Fig. 1;

Fig. 3 is a vertical transverse section 80 through the lower portion of the door opening and door, including the floor and channel sill supporting the floor.

Fig. 4 is a horizontal section on the line 4—4 of Fig. 3, looking downwardly, with the door in closed position; and 85

Fig. 5 is a similar section showing the door slid to open position.

Referring to the drawings, 6 designates the channel sill of the car, 7 the floor supported on the sill 6, 8 one of the side walls in which is formed the door opening 9, and 10 the door posts, either metal or wood as preferred, at either side of the opening 9. 90 As clearly shown in Figs. 2 and 3, the floor of the car at the opening overhangs the vertical plane of the side wall 8; this overhanging portion of the floor constituting the door sill being designated by 7'. 11 designates the car door supported either 95 from the top or bottom as preferred.

To the outer face of the car sill 6 and the under side of the door sill 7' directly beneath and preferably for the full width of

the door opening is a bar 12 herein shown as of angular form, attached through its vertical limb to the sill 6 by rivets 13 and to the under side of the door sill 7 by bolts 14 and nuts 15 countersunk in the sill 7. The horizontal limb of the angle bar 12 is formed with a depending flange 16 extending the full length thereof and constituting the stationary element of a door-guiding and retaining device forming an important feature of the present invention. It will be observed by reference to Fig. 3 that the guiding and retaining member 16 lies inwardly of the vertical plane of the outer edge of the door sill 7. Secured to the lower edge of the door 11, as by bolts 17, the heads of which are preferably countersunk on the inner side of the door, is a channel shaped bar 18, the horizontal limb of which extends inwardly and terminates in an upwardly directed flange 19 that lies behind and is slightly spaced from the depending flange 16 of the bar 12. The flanges 16 and 19 co-operate in an obvious manner to lock the lower portion of the door against swinging outwardly from the door opening under pressure of the lading or from any other cause. While the bar 12 preferably extends the full width of the door opening, a plurality of shorter bars may be used instead without detracting from the principles of my invention.

In order that the door, when fully closed, may be held tightly against the outer faces of the posts 10 and against rattling, the rear face of the flange 16 is formed with a cam-like protuberance or bulge 20, near one end thereof, while the flange 19 carried by and movable with the door is formed near the other end thereof with a similar cam protuberance or bulge 21 on its front face. As the door is slid to the fully closed position indicated in Figs. 1, 2 and 4, the upstanding flange 19 rides over the bulge 20 and at the same time the bulge 21 on the member 19 rides over the other end of the flange 16; the two cam projections or bulges thus co-operating to pull the lower end of the door inwardly and tightly against the outer faces of the posts 10, and hold it in such position.

In order to prevent the lower end of the door from swaying outwardly when the door is open, I provide on the sill 6 one or more of guiding and retaining devices 22, shown in Figs. 1, 2 and 5. These may conveniently take the form of short sections structurally similar to the angle bar 12 with its depending flange 16; except, that to insure the engagement of the door flange 19 with the guiding and retaining devices 22, the depending flanges 23 of the latter are spaced slightly further outwardly than in the case of the flange 16 on the angle bar 12. The guiding members 22 are spaced apart a distance somewhat less than the

width of the door, so that, when the latter is fully opened, it is engaged and retained at its lower portion by both of said devices.

The vertical edges of the door 11 are preferably bound by angle strips 24; and to the outer side of one of the posts 10 is secured a stop plate 25. To the inner side of the door adjacent to its other vertical edge is preferably attached a weather strip 26 adapted to co-operate with the front flange 75 of the other door post 10 when the door is in fully closed position.

The foregoing description, in connection with the drawing, will make clear to persons skilled in the art how the stated objects of the invention are attained by the described construction. It will be seen that both of the co-operating door guiding and locking flanges 16 and 19 are located inwardly of the vertical plane of the floor of the car at the opening, where it is impossible for them to be bent, broken, or otherwise damaged through contact with the lading or with trucks. It will also be noted that the fastenings 13 and 14 of the stationary guiding and locking flange 16 are both approximately in the line of outward thrust on the flange 16 resulting from pressure on the inner side of the door or the tendency of the door to swing outwardly under swaying movements of the car, so that there is no prying strain on said fastenings, such as occurs in the case of brackets of the old construction above referred to, which are riveted to the lower portion of the sill at a considerable distance below the lower edge of the door. The cams 20 and 21 act automatically to draw the door snugly against the vertical posts or margins of the opening when it is closed, and the stop 25 and strip 26 both serve as weather strips. By extending the guiding and retaining flange 16 the full width of the door, the latter is manifestly held against outward pressure at its bottom over its entire width. Again, the door cannot be unlocked at its bottom by prying it upwardly and then outwardly, as has frequently been done by thieves and pilferers with the old bracket guide construction hereinbefore referred to, nor can it be so unlocked at its bottom by internal pressure of the lading bulging the same outwardly, since upward and outward pressure cause the guiding and locking members 16 and 19 to engage with each other only the more tightly and securely.

While I have herein shown and described one practical and useful form in which the principle of the invention may be embodied it is manifest that changes in the details of structure and arrangement may be resorted to without involving any departure from the operative principle of the invention or sacrificing any of the advantages inherent therein. Hence I do not limit the in-

vention to the exact details shown and described for the purposes of illustration and information, but reserve all such variations and modifications as fall within the spirit and purview of the appended claims.

I claim:

1. In a car door construction, the combination with a car body having a door opening in a wall thereof, and a sliding door, of a guiding and retaining member for the bottom of said door located inwardly of the outer vertical plane of the door sill, and a co-operating guiding and retaining member on said door.
2. In a car door construction, the combination with a car body having a door opening in a wall thereof, a door sill at the bottom of said opening, and a sliding door, of a metal strip attached to the under side of said door sill and having a depending flange disposed inwardly of the outer edge of the latter, and a metal strip attached to said door and formed with an upstanding flange lying behind said depending flange and co-operating with the latter to hold said door against outward movement.
3. In a car door construction, the combination with a car body having a door opening in a wall thereof, a door sill at the bottom of said opening, and a sliding door, of a metal strip attached to the under side of said door sill and formed with a depending flange extending the full width of said door sill and disposed inwardly of the outer edge of the latter, and a metal strip secured to the bottom of said door formed with a rearwardly extending horizontal portion underlying said depending flange and an upstanding flange lying behind said depending flange and co-operating with the latter to hold said door against outward movement.
4. In a car door construction, the combination with a car body having a door open-
- ing in a wall thereof, and a sliding door, of a guiding and retaining member for the bottom of said door located inwardly of the outer vertical plane of said door opening, a co-operating guiding and retaining member carried by said door, and co-operating means on said guiding and retaining members for drawing the door inwardly as it is slid to its closed position.
5. In a car door construction, the combination with a car body having a door opening in a wall thereof, and a sliding door, of a metal strip attached to the car and having a depending flange disposed inwardly of the outer vertical plane of said opening, a metal strip attached to said door and formed with an upstanding flange lying behind said depending flange, and cams on the opposed faces of said flanges, respectively, each co-operating with the other flange as the door is slid to closed position, to draw the bottom of the door inwardly.
6. In a car door construction, the combination with a car body having a door opening in a wall thereof, a door sill at the bottom of said opening, and a sliding door, of a metal strip secured to and extending inwardly of the bottom of said door and formed with an upstanding flange, a metal strip attached to the under side of said door sill and having a depending flange disposed inwardly of the outer edge of said door sill and in front of said upstanding flange when the door is closed, and a plurality of spaced metal strips attached to the car at one side of said door opening and formed with depending flanges disposed in front of said upstanding flange when the door is open and co-operating with said upstanding flange to hold the open door against outward movement.

EARL F. JAGER.
